UNITED STATES PATENT OFFICE

FRIEDRICH HELMRICH, OF MAGDEBURG, GERMANY, ASSIGNOR TO THE FIRM FRIED.
KRUPP GRUSONWERK AKTIENGESELLSCHAFT, OF MAGDEBURG-BUCKAU, GERMANY

ECCENTRIC OR DRAW ROD FOR STONE CRUSHERS

Application filed January 13, 1931, Serial No. 508,502, and in Germany February 2, 1930.

The present invention has reference to an eccentric rod or draw rod for stone crushers, of the type formed with a head adapted to embrace the bearing surrounding the eccentric. Known constructions of such eccentric rods present several inherent drawbacks. The assembling and dismantling of the brasses or bushes is difficult; the action of the cooling and lubricating devices is also unsatisfactory and their points of application are not advantageously situated. As a result of this invention all these drawbacks are obviated, by predetermining the dimension of the head in the axial direction and recessing the draw rod immediately below the bearing by a definite minimum amount.

Due to the selection of the axial dimension of the head the lubricating and cooling conditions are more favourable and the dismantling of the bearings is facilitated, largely on account of the recess in the draw rod. Replacement of the brasses or bushes has heretofore been greatly hampered, in the longitudinal direction of the draw rod by the lateral shaft bearings, and in the axial direction by the fly wheels located close to the shaft bearings. The removal of the brasses or bushes was also difficult inasmuch as a grasp of the bushes according to the type of construction hitherto used was hardly possible, especially in view of the considerable weight of the brasses or bushes, which, for example, in the case of large stone crushers amounts to from 60-70 kg.

The invention consists in the fact that the head of the draw rod is made of such a breadth that the brasses can be drawn out sideways between the draw rod and the fly wheels, whilst the recess around the lower bearing brass extends in the longitudinal direction of the draw rod by at least the distance between the axis of either side bearing and its upper extremity.

From such a construction of draw rod there, consequently, result the following advantages in comparison with those already known. The brasses can be very easily grasped, which is of advantage in view of their great weight, and they are, furthermore, easy of access in order to determine

their temperature. This is necessary, if consideration be given to the great pressures occurring when crushing stones or the like in conjunction with the aforesaid considerable normal weight of the brasses, whereby excessive heating may be produced. Now, due to the fact that the brasses project axially beyond the head of the rod, this heating is substantially reduced on account of the cooling effect of the air circulated by the movement of the head. However, water cooling can also be much better utilized than heretofore since the cooling pipe, which is connected to the cooling medium container as by a rubber pipe for example, may connect at the periphery of the brass with the cooling medium conduit provided inside the brass, whereas, according to the type of construction hitherto used, in which the brass did not project, delivery of the cooling medium had to take place at an end surface of the brass, but this was extremely difficult owing to the contiguous side bearings. In the present case it is no longer necessary that the lubricating slots lie in the neighbourhood of the greatest pressure as heretofore, as they may be mounted in a plane which approaches the axial plane lying transversely to the length of the draw rod so that the lubricating medium can be better distributed in the bearing. There is, finally, the advantage, which is of considerable value, that, owing to the restricted axial dimension of the head, any errors in the parallel arrangement of the elbow lever plates transmitting power to the crushing blade may be counterbalanced.

In the accompanying drawing, which shows one example of draw rod in accordance with the invention,

Figure 1 is a cross section through the head of the draw rod, and

Figure 2 an axial section through the head bearing and lateral bearings, showing also the fly wheels.

1 is the head of the draw rod, the axial length of which, as seen in Figure 2, must not exceed the difference between the distance, y , separating the fly wheels 2 and double the length, z , of the brasses 5, 5' of the eccentric rod. The recess 3 in the draw rod

immediately below its bearing must be of such a length x that the clearance between the outer surface of the inner brass 5 and the opposite edge of the rib 4 is not less than 5 the distance between the centre of the axis of either lateral bearing 6 and the upper surface of the bearing cover 7 or, in the present example, the upper end of the bearing cover screws 8. In Figure 2 there is shown in dot-and-dash lines the position of a bearing brass 9 as withdrawn and also the corresponding position of the draw rod head 1 (see also Figure 1).

As may be seen from Figure 1, a lubricating cup 10 may be inserted close to the horizontal plane passing through the axis of the shaft, this being feasible because of the laterally projecting parts of the bearing brasses 5', seen in Figure 1. In the same part of the bearing there open, if necessary, the cooling medium conduits 11. The lower bearing brass 5 is carried by screw bolts 12 and pressed against the upper bearing brass 5' so that it is prevented from rotation and is at the same time held firmly in position.

What I claim is:—

1. In the combination of a stone crusher, a drive shaft, an eccentric on said drive shaft, lateral bearings for said shaft on both sides 30 of said eccentric, a flywheel mounted on said shaft beyond one of said lateral bearings, a bearing bush composed of two semi-cylindrical halves disposed upon said eccentric, a draw rod having a head integral therewith fixed to the bearing bush, a recess in said head immediately below the bearing bush at least as long as the distance between the axis of one of the lateral bearings and the upper extremity thereof, said head being shorter in 40 axial length than said bearing bush and centrally disposed upon said bush, having the edge thereof nearer the flywheel spaced from said flywheel a distance greater than the axial length of said bearing bush.

45 2. In the combination of a stone crusher, a drive shaft, an eccentric on said drive shaft, lateral bearings for said shaft on both sides of said eccentric, a flywheel mounted on said shaft beyond one of said lateral bearings, a bearing bush composed of two semi-cylindrical halves disposed upon said eccentric, a draw rod having a head integral therewith of smaller axial length than said bearing bush mounted upon said bush, the edge of said 55 head near the flywheel being spaced from said flywheel a distance greater than the axial length of said bearing bush to permit the lateral removal of said bush intermediate the head of the draw rod and the flywheel, and a recess in said draw rod immediately below said bearing bush to permit the radial movement of said head and bush an extent sufficient to clear the upper external boundaries of said lateral bearing adjacent said flywheel.

3. In the combination of a stone crusher, a drive shaft, an eccentric on said drive shaft, lateral bearings for said shaft symmetrically mounted upon both sides of said eccentric, flywheels mounted on said shaft beyond said 70 lateral bearings, a bearing bush composed of two semi-cylindrical halves disposed upon said eccentric, a draw rod having a head integral therewith fixed to the bearing bush, the axial length of said head being less than the difference between the distance separating the flywheels and double the length of the bearing bush, to permit the lateral removal of said bush intermediate the head of the draw rod and either flywheel, and a recess in said draw rod immediately below said bearing bush to permit the radial movement of said head and bush an extent sufficient to clear the upper external boundaries of said lateral bearings.

4. The combination claimed in claim 2, wherein lubricating means is applied to the peripheral surface of the bearing bush at the side of the head of the draw rod.

5. The combination claimed in claim 2, wherein cooling means is applied to the peripheral surface of the bearing bush at the side of the head of the draw rod.
